DESIGN FOR A SAND BOX

Peter A. Cosme, Chicago, Ill.

Application August 17, 1945, Serial No. 121,439

Term of patent 14 years

(Cl. D34—5)

To all whom it may concern:

Be it known that I, Peter A. Cosme, a citizen of the United States of America and a resident of Chicago, county of Cook, and State of Illinois, have invented a new, original, and ornamental Design for a Sand Box, of which the following is a specification, reference being had to the accompanying drawing, forming a part thereof.

Fig. 1 is a side and front perspective of a sand box, showing my new design.

Fig. 2 is an opposite side and rear perspective view of the same.

Fig. 3 is a side elevational view of the same.

Fig. 4 is a fragmentary rear elevational view of the same.

I claim:

The ornamental design for a sand box, substantially as shown.

PETER A. COSME.
